UNITED STATES PATENT OFFICE.

FRANK B. HOWELL, OF BUFFALO, NEW YORK, ASSIGNOR TO AMERICAN RADIATOR COMPANY, OF CHICAGO, ILLINOIS, A CORPORATION OF NEW JERSEY.

HEATING APPARATUS.

1,239,430.

Specification of Letters Patent. Patented Sept. 4, 1917.

Original application filed November 14, 1914, Serial No. 872,122. Divided and this application filed October 14, 1915. Serial No. 55,773.

To all whom it may concern:

Be it known that I, FRANK B. HOWELL, a citizen of the United States, residing at the city of Buffalo, Erie county, in the State 5 of New York, have invented certain new and useful Improvements in Heating Apparatus, of which the following is a full, clear, and exact specification.

My invention relates to improvements in 10 heating apparatus, and the same has for its object more particularly to provide a simple, efficient and reliable stove in which the fuel receptacle or fire box is constructed and arranged to maintain the fuel in the form 15 of a relatively thin or narrow vertical column through which the draft is passed crosswise or horizontally.

Further, said invention has for its object 20 to provide a stove having a fire box or fuel receptacle, combustion chamber and its draft passages and appurtenances so constructed and arranged to permit of the burning of all kinds of fuel economically and smokelessly.

25 Further, said invention has for its object to provide a stove having a fire box or fuel receptacle in which the air necessary to support combustion is not permitted to enter the fire box or fuel receptacle directly but 30 is conducted longitudinally thereof through heated flues arranged at one side of the receptacle, and at the back thereof, in order to preheat the air, and thence conducted to the opposite side of the receptacle where it 35 is delivered to the interior of the fire box or fuel receptacle in a series of superposed, parallel, horizontal streams or jets.

Other objects will in part be obvious and in part be pointed out hereinafter.

40 To the attainment of the aforesaid objects and ends my invention consists in the novel details of construction, and in the combination, connection and arrangement of parts hereinafter more fully described and then 45 pointed out in the claims.

In this application I do not claim the general construction of the stove as a whole, as the same forms the subject matter of another application filed by me on November 14, 1914, Serial No. 872,122, of which this application is a division. In the present application, therefore, I have shown, described and claimed the fire box or fuel receptacle apart from the stove generally.

In the accompanying drawings forming 55 part of this specification wherein like numerals of reference indicate like parts,—

Figure 1 is a front elevation showing one form of range or stove provided with a fire box or fuel receptacle constructed according 60 to and embodying my said invention;

Fig. 2 is a top view thereof;

Fig. 3 is an end view partly in section on the line 3—3 of Fig. 5;

Fig. 4 is a vertical section at right angles 65 to Fig. 3, and taken on the line 4—4 of Fig. 6;

Fig. 5 is a vertical section taken on the line 5—5 of Fig. 6, and

Fig. 6 is a horizontal section taken on the 70 line 6—6 of Fig. 5.

10 represents the fire box or fuel receptacle which occupies one side of the stove, as shown in the drawings the left hand side when viewed from the front. Positioned 75 above the fuel receptacle is the combustion chamber 10'. 11 represents the oven which occupies the upper right hand portion of the stove, and 12 represents the water heater which occupies the portion underneath the 80 oven, which is the lower right hand portion, as shown in the drawings.

13 represents the top plate which extends over the combustion chamber and the oven and is provided with a suitable number of 85 openings for cooking vessels. The openings are provided with the usual covers 14. The exit opening 15 for connection with the stove pipe is arranged in this top plate in rear of the oven.

90 The fuel receptacle 10 is high and narrow in order to hold the fuel in the form of a tall column which is narrow in the direction in which the draft passes through the fuel and has its draft passages so arranged that 95 the draft passes transversely through the column of fuel from one side to the other. In the construction shown in the drawings, the draft passes through the fuel receptacle transversely from the side thereof which is 100 adjacent to the end of the stove toward the side thereof at which the oven and the water heater are arranged.

The air for the support of combustion enters an upright air chamber 16 which 105 forms the narrow front wall of the fuel receptacle and which is provided in its front plate with a vertical series of air inlet open-

ings 17. Air inlet passages 18 extend in line with these openings through the insulated or lined outer wall 19 of the stove, Fig. 6. The inlet openings 17 are controlled by a vertically adjustable register plate 20, Figs. 1, 3, 5 and 6, having openings 21 corresponding with the openings 17. This register plate is provided with a handle 22, Figs. 1 and 3, by which it can be moved up or 10 down.

The exit wall of the fuel receptacle is formed by a vertical series of spaced hollow bars 23, the cavities of which form air passages communicating at their front or inlet 15 ends with the front air chamber 16 and at their outlet ends with an upright air chamber 24 forming the narrow rear wall of the fuel receptacle. These hollow bars extend lengthwise from the front air chamber 16 20 to the rear air chamber 24 and are separated by draft exit passages 25 through which the flame and hot gases escape from the fuel receptacle. The upper and lower sides of these hollow bars are inclined so as to rise 25 in the direction of the draft and away from the column of fuel in order to confine the latter within the fuel receptacle. This upright series of hollow bars connects the front and rear air chambers and forms an upright 30 grate between these chambers on the exit side of the fuel receptacle.

26 represents spaced bars which constitute an upright grate on the inlet draft side of the fuel receptacle and extend from the rear 35 to the front air chamber of the same. These bars are inclined like the hollow bars 23 but are solid and are separated by air passages 27 into which the air is delivered from the rear air chamber 24 through openings 28 in the adjacent plate of the rear air chamber, Figs. 4 and 6. These solid bars 26 are preferably provided on their under sides along their edges with longitudinal ribs 29, 30, Fig. 4, to better confine the air 40 currents, which ribs give these bars an inverted channel form.

In the operation of this fuel receptacle the air for the support of combustion enters the front air chamber 16, passes through 50 the hollow bars 23 of the exit grate, then through the rear air chamber 24, and then through the spaces between the solid bars 26 of the indraft grate and enters the fuel receptacle through the passages 27 between 55 the bars 26. These chambers and bars are constructed of cast iron or other suitable material and become highly heated by the burning fuel, and consequently the air passing in contact with these hot surfaces of 60 the front air chamber, the hollow bars of the exit grate, and the rear air chamber becomes highly heated and issues into the column of fuel at the indraft side of the fuel receptacle in a highly heated state, whereby 65 the complete combustion of the fuel is pro-

moted and the formation of smoke is practically avoided.

31 represents supplemental air inlet openings formed in the end wall 32 of the stove at the indraft side of the fuel receptacle and in line with one or more of the air passages between the indraft bars 26. These openings are controlled in any suitable manner, for instance, by pivoted covers 33, and may be employed if the nature of the fuel requires an additional air supply to the fuel receptacle.

34, Figs. 4, 5 and 6, represents an upright main flue which is arranged on the exit side of the fuel receptacle. The exit draft passages 25 between the hollow bars 23 open into this flue from which the draft is directed in various ways through branch flues, as the user may desire. The upper portion of this main flue extends across the indraft side of the oven which is separated from this flue by an upright partition or plate 35 extending from the top plate of the oven to the bottom plate thereof and from the front wall to the rear wall of the stove. Above this upright partition and underneath the top plate of the stove there is arranged a damper 36 which controls the passage leading from the upper end of this flue to a horizontal flue 37 which is arranged between the top of the oven and the top plate of the stove and which communicates with the exit opening 15 with which the stove pipe is connected. Upon opening this damper, as shown in Fig. 4, the draft passes directly from the upper end of the upright main flue to the exit opening 15, and the heat is practically concentrated upon the top plate of the stove and cut off from the oven and from the water heater. By closing this damper, as shown in Fig. 5, the draft is prevented from passing directly to the exit opening 15.

38 represents a horizontal baffle plate arranged underneath the oven and above the water heater, and separated from the bottom of the oven by a horizontal intermediate flue 39 which communicates at the rear side of the stove with an upright flue extending upwardly on the rear side of the oven to the horizontal top flue 37. The lower portion of the upright main flue 34 is arranged adjacent to the water heater from which it is separated by an upright partition or plate 41 which extends from the horizontal baffle plate 38 downwardly and is separated at its lower end from the bottom of the stove by a draft passage 42. The horizontal baffle plate 38 is provided near the main flue 34 with draft passages 43. The passage leading from the main flue to the horizontal flue 39 beneath the bottom of the oven is controlled by a damper 44. Upon closing the latter and the top damper 36 the draft is directed downwardly through the main flue 125 130

and through the bottom passage 42 to the lower portion of the space in which the water heater is arranged. The draft passes upwardly through this space, supplying heat 5 to the water heater, and passes through the passages 43 in the horizontal baffle plate 38 into the horizontal flue 39 and thence through the upright rear flue 40 to the exit opening 15 to which the stove pipe is connected.

10 Upon closing the upper damper 36 and opening the lower damper 44 the draft is directed from the main flue 34 to the horizontal flue beneath the oven and cut off from the water heater. In this position of the 15 dampers the heat is utilized mainly for heating the top plate and the oven, as in cooking and baking, and but little heat is supplied to the water heater.

The water heater shown in the drawings 20 is composed of several connected sections or chambers and provided with a flow pipe 45 and a return pipe 46. It may also be provided with a faucet 47 for drawing off hot water. The particular construction of 25 the water heater is unimportant and any suitable construction may be employed.

48 represents the grate, 49 the ash pit, 50 the ash pit door, 51 the oven door, and 52 the door leading to the space in which the water 30 heater is arranged.

Having thus described my said invention, what I claim and desire to secure by Letters Patent is:—

1. In a stove, a fuel receptacle comprising 35 a hollow front wall having air inlet openings therein, a hollow rear wall having outlet openings therein, a series of hollow bars connected at their opposite ends to said hollow front and rear walls and forming 40 one side of said fuel receptacle, and a series of bars extending from said hollow front wall to said hollow rear wall adjacent to the air outlets in the latter and forming the other side of said receptacle, substantially 45 as specified.

2. In a stove, a fuel receptacle comprising 50 a hollow front wall having inlet openings therein and means for controlling said inlet openings, a hollow rear wall having a corresponding series of air outlet openings therein, a series of hollow bars connected at their opposite ends to said front and rear walls and forming one side of said fuel receptacle, and a series of solid bars similarly 55 arranged extending from said hollow front wall to said hollow rear wall, adjacent to the air outlets therein, and forming the other side of said receptacle, substantially as specified.

60 3. In a stove, a fuel receptacle comprising a hollow front wall having a series of inlet openings therein and means for simultaneously controlling the extent of the openings of said inlet openings, a hollow rear wall having a corresponding series of air

outlet openings therein, a series of hollow bars connected at their opposite ends to said front and rear walls and forming one side of said fuel receptacle, and a series of solid bars similarly arranged extending from 70 said hollow front wall to said hollow rear wall, adjacent to the air outlets therein, and forming the other side of said receptacle, substantially as specified.

4. In a stove, a fuel receptacle comprising 75 a hollow front wall having a series of inlet openings, a sliding plate having corresponding openings therein adapted to control the admission of air to the inlet openings in said hollow front wall, a hollow rear wall 80 having a corresponding series of air outlet openings therein, a series of hollow bars connected at their opposite ends to said front and rear walls and forming one side of said fuel receptacle, and a series of 85 solid bars similarly extending from said hollow front wall to said hollow rear wall, adjacent to the air outlets therein, and forming the other side of said receptacle, substantially as specified.

5. In a stove, a fuel receptacle comprising 90 a hollow front wall having a vertical series of air inlet openings therein, a hollow rear wall having outlet openings therein, a series of superposed, transversely-inclined hollow 95 bars connected at their opposite ends to said hollow front and rear walls and forming one side of said fuel receptacle, and a series of superposed, transversely-inclined solid bars extending from said hollow front wall to 100 said hollow rear wall, adjacent to the air outlets therein, and forming the other side of said fuel receptacle, substantially as specified.

6. In a stove, a fuel receptacle comprising 105 a hollow front wall having a vertical series of air inlet openings therein, a hollow rear wall having outlet openings therein, a series of superposed, transversely-inclined hollow 110 bars connected at their opposite ends to said hollow front and rear walls and forming one side of said fuel receptacle, a series of superposed, transversely-inclined solid bars extending from said hollow front wall to 115 said hollow rear wall, adjacent to the air outlets therein, and forming the other side of said fuel receptacle and means for conducting air from said air outlets along the undersides of said bars, substantially as specified.

7. In a stove, a fuel receptacle comprising 120 a hollow front wall having a vertical series of air inlet openings therein, a hollow rear wall having outlet openings therein, a series of superposed, transversely-inclined hollow 125 bars connected at their opposite ends to said hollow front and rear walls and forming one side of said fuel receptacle, and a series of superposed, transversely-inclined solid bars extending from said hollow front wall 130

to said hollow rear wall, and provided in their undersides with longitudinal channels communicating with the air outlets in said hollow rear wall, said solid bars forming 5 the other side of said fuel receptacle, substantially as specified.

8. In a stove, an upright fuel receptacle having an upright series of draft inlets on one side and an upright series of draft outlets on the opposite side, front and rear air chambers, means for admitting air to said front air chamber, means for conducting the air from said front air chamber to said rear air chamber, and means for delivering the 10 air from said rear air chamber to said draft inlets, substantially as specified.

9. In a stove, a fuel receptacle comprising air chambers forming the front and rear walls thereof, hollow bars connecting said 20 chambers and communicating therewith, said bars being separated by draft outlet passages and forming the wall of the fuel receptacle on the outlet side thereof, bars forming the opposite wall of the fuel receptacle and separated by draft inlet passages, means for admitting the air to said front chamber, and means for delivering the air from said rear air chamber to 25 said draft inlet passages, substantially as 30 specified.

10. In a stove, an upright fuel receptacle comprising front and rear air chambers, means for admitting air to said front air chamber, hollow bars communicating with 35 said air chambers and forming an upright grate on the exit side of said fuel receptacle, bars forming an upright grate on the inlet side of the fuel receptacle, and means for

discharging the air from the rear air chamber into the spaces between the bars on the 40 inlet side of the fuel receptacle, substantially as specified.

11. In a stove, an upright fuel receptacle comprising front and rear air chambers, means for admitting the air to said front air 45 chamber, an upright grate arranged on the exit side of said fuel receptacle and having hollow bars connecting the air spaces of said front and rear chambers, an upright grate arranged on the indraft side of said fuel 50 receptacle and provided with indraft passages, means for delivering the air from said rear air chamber to said indraft passages, and means for admitting outside air directly to said indraft passages, substantially as 55 specified.

12. In a stove, a fuel receptacle comprising front and rear air chambers, means for admitting the air to said front air chamber, air passages conducting the air from said 60 front air chamber to said rear air chamber, draft exit and draft inlet passages formed between said air chambers on opposite sides of said fuel receptacle, and means for delivering the air from said rear air chamber 65 to said draft inlet passages, substantially as specified.

Signed at the city of Buffalo, Erie county, in the State of New York, this 19th day of August, one thousand nine hundred and 70 fifteen.

FRANK B. HOWELL.
